LITHOGRAPHIC OFFSET PRESS

Joseph Schultz, Cleveland, Ohio

Application May 31, 1932, Serial No. 614,408

16 Claims. (Cl. 101—147)

My invention relates to a lithographic press, and more particularly to presses of this class in which the design is engraved on a zinc plate mounted on a plate cylinder, and which design is inked and transferred to a rubber blanket which in turn offsets the design upon paper, this press being known as a lithographic offset press. More specifically this invention relates to a particular arrangement of the various cylinders in the press 10 with relation to each other, and to the location of a dampening device and ink rollers with relation to the plate cylinder, this arrangement of cylinders and location of rollers producing certain advantages which will be hereinafter pointed out.

15 The subject matter of this invention is a further development of inventions disclosed in my Patents numbered and entitled as follows: No. 1,812,720, entitled: Dampening device; No. 1,958,593, entitled: Method of and apparatus for 20 dampening in lithographic presses; No. 1,969,154, entitled: Dampening device for lithographic offset presses and the like; No. 1,969,155, entitled: Dampening mechanism for lithographic offset presses and the like; No. 1,991,962, entitled: 25 Dampening device for lithographic offset presses and the like; and certain features of this invention described and/or shown in this application, and not claimed herein, are claimed in said earlier patents. Certain other features disclosed in this 30 application and not claimed herein, are claimed in my Patent No. 1,976,532 entitled: Method of and mechanism for feeding sheets in lithographic presses.

As is well known to those skilled in the art of 35 offset lithography, it is frequently necessary for the operator to have access to the plate cylinder of a lithographic press for the purpose of inspecting the plate, for the purpose of shifting the plate, for the purpose of cleaning or gumming the plate, 40 and for the purpose of mounting the plate on the cylinder and removing it from the cylinder. It is also frequently necessary that the plate be conveniently accessible so as to enable the artist to make changes in the plate while it is on the press.

45 All lithographic presses now generally used, and all presses disclosed in the patented art, so far as I am aware, provide access to the plate for the purposes pointed out. The portion of the 50 plate which is accessible, however, is a relatively small part of the whole plate, and is usually relatively inconvenient of access. Inasmuch as the exposed periphery of the plate is usually relatively narrow in the direction of movement of the 55 plate, it is necessary to move the plate several

times in order that the entire plate may be inspected, cleaned or gummed.

It is also well known to those skilled in this art that the blanket cylinder must be readily accessible for the purpose of mounting the blanket 5 on the cylinder, for the purpose of washing the blanket, for the purpose of changing the packing underneath the blanket and for the purpose of making any necessary repairs on the blanket.

As built at present, the blanket cylinder is us- 10 ually very inaccessible, because the plate cylinder is generally located vertically above the blanket cylinder. In addition other mechanism is located around the blanket cylinder making it exceeding- 15 ly difficult to have access to the blanket cylinder. 15

Present lithographic presses frequently pro- 20 duce gear marks on the printed sheets due to the backlash or play between the teeth of the driving gears on the cylinders, and also produce defects caused by the shift of the blanket cylinder and the 25 impression cylinder, or the blanket cylinder and the plate cylinder, during the printing.

In all lithographic presses known to me, the diameters of the plate ink rollers are considerably 25 smaller than the diameter of the plate cylinder. The result of this is that some portion of the periphery of each plate ink roller contacts the 30 surface of the design on the plate two or more times. On heavily inked designs, as a result of this second contact of the plate ink rollers with 35 the design, the printed area near the gripping edge of the sheet is frequently darker than the printed area on the other edge of the printed sheet.

One of the objects of this invention therefore, is 35 to produce an arrangement of cylinders in a lithographic press in which a maximum of the periphery of the plate cylinder is accessible for the purpose of mounting the lithographic plate on the plate cylinder and adjusting it with relation to the plate cylinder. 40

A further object is to produce a press in which a maximum area of the lithographic plate mounted on the plate cylinder is readily accessible for the purpose of inspection, cleaning or gumming 45 the plate and making changes or additions in the design on the plate.

A further object is to produce a lithographic offset press in which the plate may be accessible 50 for the purposes set forth, when the plate is on top of the plate cylinder.

A further object is to produce a novel arrangement of cylinders in a lithographic offset press in which a maximum of the upper portion of the 55 periphery of the blanket cylinder is accessible for

the purpose of mounting and removing the blanket from the blanket cylinder, and for the purpose of washing the blanket, changing the packing underneath the blanket and making any necessary repairs on the blanket.

A further object is to produce an arrangement of cylinders and mounting for a dampening device which permits the application of moisture to the lithographic plate, substantially on the top of the periphery of the cylinder.

A further object of this invention is to produce a mounting for dampening mechanism which permits the shifting of the entire dampening mechanism from co-operative engagement with the plate to a position sufficiently remote from the plate to permit complete access of the operator to the plate, at the dampening position.

A further object of this invention is to produce a dampening apparatus for a lithographic press which can be swung sideways to a position laterally of the press whereby the dampening apparatus is completely eliminated as an obstruction and does not interfere with the access of the operator to any portion of the top of the press.

Another object of this invention is to produce such an improved portable or shiftable type of dampening apparatus for a lithographic press, in which moisture is transferred to the plate by means of an absorbent sheet or apron gravitationally resting upon or lightly pressing against the face of a lithographic press and in which a controllable amount of moisture may be fed to any point transversely of the sheet.

A further object is to produce such an improved type of shiftable dampening apparatus for a lithographic press in which the device which contacts the plate and which actually applies the moisture to the plate is automatically reciprocated transversely of the plate to uniformly distribute the moisture upon the plate, and in which the reciprocating mechanism is automatically actuated when the dampening mechanism is in its operative position with relation to the plate cylinder, and in which the actuation ceases when the dampening mechanism is shifted to an inoperative position.

A further object is to produce a lithographic press of the cylinder type in which the periphery of the plate inking roller contacting the plate is substantially equal to the peripheral length of the design on the plate, so that no portion of the periphery of the plate inking roller or rollers will contact the design on the plate more than once during any one impression.

A further object is to produce a novel arrangement of gearing for driving the cylinders in a lithographic press, which maintains a maximum of perfection of the registry between these cylinders during the operation of the press, eliminating gear marks, or other defects on the printing, resulting, from backlash or relative movement of any cylinder with relation to any other cylinder during the offsetting or printing process.

Further objects and advantages of this invention will appear from the following description and from reference to the accompanying drawings.

These annexed drawings and description set forth in detail certain means embodying this invention, such disclosed means constituting however, but two forms in which the principle of this invention may be applied.

In said annexed drawings:

Figure 1 is a plan view of a lithographic offset press embodying my invention, certain parts of

the press which are not a part of this invention being omitted.

Figure 2 is a longitudinal section through the press shown in Figure 1, this section being taken on the plane indicated by line 2, 2 in Figure 1, and showing the arrangement of driving gears for certain inking rollers and dampening mechanism.

Figure 3 is a view of a fragmentary portion of the operator's side of the press showing means 10 for locking a certain shiftable dampening device in operative relation with the plate cylinder, this view being taken from the plane indicated by line 3, 3 in Figures 1 and 10.

Figure 4 is a longitudinal section through the press shown in Figure 1, this section being taken on the plane indicated by line 4, 4 in Figure 1.

Figure 4a is a small scale diagrammatic view of a modification of this invention similar to Figure 4 but showing certain parts tilted to assume a different angular position.

Figure 5 is a side elevation of the press shown in Figure 1, this view showing the operator's side of the press.

Figure 6 is a fragmentary view of a portion of Figure 4, showing certain parts in an alternative position.

Figure 7 is a plan view of this improved press, similar to Figure 1, but showing the dampening device, constituting an important element of this invention, swung away from the plate cylinder with which it normally co-operates.

Figure 8 is a longitudinal section taken on the plane indicated by line 8, 8, in Figure 1.

Figure 9 is a section through the dampening device taken on the plane indicated by line 9, 9, in Figure 7.

Figure 10 is a fragmentary elevational view of the upper portion of the press, this view being taken from the plane indicated by line 10, 10 in Figures 4, 5, and 8, and being broken away to disclose certain elements normally concealed.

Figure 11 is a fragmentary plan view of one of the improved mechanisms of this invention, this view being taken from the plane indicated by line 11, 11 in Figures 4 and 5, certain liquid supplying elements being omitted.

Figure 12 is a fragmentary section of the upper portion of the press taken on the plane indicated by line 12, 12 in Figures 4, 5, and 8.

Figure 13 is a sectional view taken on the plane indicated by line 13, 13 in Figure 11, this view showing certain mechanism for actuating a portion of the dampening device.

Figure 14 is a fragmentary enlarged view of one of the brackets shown in Figure 13.

Figure 15 is an enlarged fragmentary detached view of one detail feature of this invention, this view being taken from the plane indicated by line 15, 15 in Figure 10.

Figure 16 is a view similar to Figure 15 showing a certain element in an alternative position.

Figure 17 is a fragmentary enlarged view of a portion of Figure 4, the portion shown being the upper portion of the impression cylinder and the adjacent portion of the blanket cylinder, together with grippers and stops mounted upon and/or co-operating with this portion of the impression cylinder.

Figure 18 is another view similar to Figure 17, but showing the moving parts in a more advanced position.

Figure 19 is still another view, similar to Figure 17, but showing the parts in a still further advanced position.

Figure 20 is a side elevation of a fragmentary portion of a lithographic press equipped with a modified form of this invention.

Figure 21 is a fragmentary plan view showing one end of the modification shown in Figure 20, this view being taken from the plane indicated by lines 21, 21 in Figures 20 and 22, the liquid reservoir being removed in this view.

Figure 22 is a fragmentary, vertical, longitudinal section through the mechanism shown in Figures 20 and 21, this view being taken on the plane indicated by line 22, 22 of Figure 21.

Figure 23 is a view similar to Figure 22 showing another modification of one detail of this invention.

In the drawings, only so much of a lithographic offset press is illustrated as bears direct relation to this invention.

The drawings illustrate one form of this invention in general and detail views, and the drawings further illustrate a modified form of this invention. This invention is shown, in the preferred form, embodied in a relatively small lithographic press which is especially designed for high speed production of first quality work, but it will be understood that this invention can equally well be applied to lithographic presses of larger sizes with proportionately greater advantages resulting from its use with such larger presses.

General description

I shall first describe the several principal features of this improved press in general terms, and shall later describe the novel features more specifically.

Referring particularly to Figures 1, 2, 4, 5, 7, and 12, 1 indicates the frame of the press comprising side frame 1a at the operator's side, and side frame 1b at the drive side of the press. Upon these frames are mounted in suitable adjustable bearings, an impression cylinder 2, a blanket cylinder 3 and a plate cylinder 4. The plate cylinder is engaged by a plurality of plate inking or form rollers 5, two being shown in the drawings. These plate inking rollers receive the uniformly distributed ink from a series of ink rollers 6 which are, in turn, supplied with ink from an ink fountain 7, in a well known manner.

The shaft 8 is the main drive shaft for this press and is driven by a belt mounted on the pulley 9. Sheets S to be printed are fed into this press from a stock pile 10 upon a tape conveyor 11 which carries them against suitable disappearing stop fingers 12 where the sheet is positioned for proper registry with the design on the plate. After the sheet S is properly registered, it is fed to the impression cylinder by a suction head 13 actuated by cam mechanism indicated generally at 14. For seizing the sheet, the rotating impression cylinder is provided with suitable grippers mechanism indicated at 15 actuated by timed mechanism to be hereinafter described. The gripper mechanism 15 is adapted to seize the sheet and cause it to travel between the peripheries of the blanket cylinder 3 and impression cylinder 2, where the sheet secures its impression. After the sheet has thus been printed, the gripper fingers feed the sheet to a delivery mechanism indicated in its entirety at 16.

The dampening device, indicated in its entirety at 17, is provided for the purpose of moistening the surface of the plate, this dampening device 75 being shiftably mounted so that it may be shifted

to a position remote from the plate cylinder, as will be hereinafter described.

An ink roller cleansing device for removing the ink from the ink rollers, when it is desired to change from one color to another, is shown at 18. 5 This device consists of a rubber wiper mounted in a frame which is adapted to be moved toward and from one of the metallic ink rollers, 6a, by means of a handle 19 mounted on the operator's side of the press. During the removal of the ink 10 from the rollers, a suitable solvent is applied to the ink rollers and the thinned ink is easily removed by the wiper and deposited in the pan 20 shown in broken lines in Figure 4.

Description of cylinders and their arrangement

The details of the plate cylinder, blanket cylinder and impression cylinder, necessary to the understanding of this invention, and the arrangement of the cylinders which is considered one of the novel and advantageous features of this invention will now be described.

The plate cylinder 4, is formed with a gap 21, in which are mounted plate holding devices 22 adapted to firmly hold the plate 23 in position 25 upon the cylinder. The plate holding devices may be of any desired construction, and include adjusting means adapted to position the plate properly on the cylinder. This plate cylinder is fixedly mounted on a shaft 24, which, in turn, is mounted in suitable bearings in the side frames 1a and 1b.

The blanket cylinder 3 is likewise formed with a gap 25 in which is mounted mechanism 26, which may be of any desired construction, adapted to hold the blanket 27 securely on the blanket cylinder 3. The blanket cylinder is fixedly mounted on a shaft 28 which is mounted in suitable bearings in the side frames 1a and 1b.

The impression cylinder 2, is likewise formed with a gap 29 in which is mounted the gripping mechanism 30 which can best be understood by reference to Figures 4, 17, 18, and 19. This mechanism consists of a plurality of gripper jaws 30 fixedly mounted on a gripper shaft 31. Likewise fixed on the shaft 31 exteriorly of one of the end walls of the cylinder is a lever 32 upon which a roller 33 is rotatably supported. This roller is held against the surface of a stationary cam 34 by means of a spring anchored on the cylinder end wall. The impression cylinder 2 is also provided with stops 35 against which the leading or gripper edge of the paper strikes as the paper is fed to the rotating impression cylinder. The contour of the surface of the cam will cause the gripping point of the gripper jaws 30 to rise or fall upon the periphery of the impression cylinder, adjacent to the stops 35, as the impression cylinder rotates. The impression cylinder is fixedly mounted on the shaft 36, which, in turn, is rotatably mounted in the frame members 1a and 1b.

As will be seen from Figure 4, the blanket cylinder 3 is located substantially vertically above 65 the impression cylinder 2, and the plate cylinder is located above but laterally of the blanket cylinder, preferably toward the delivery or rear end of the press. The plate inking or form rollers 5 engage the plate cylinder at the rear or delivery 70 side of the plate cylinder and all additional inking rollers 6 and ink fountain 7 are located to the rear of the plate inking rollers. The advantage resulting from the arrangement of cylinders will be pointed out hereinafter.

Sheet feeding apparatus

While the sheet feeding apparatus is not specifically claimed in this application, a brief description of the feeding apparatus will be necessary to a full understanding of this invention.

The sheets S to be printed are placed on the stock pile 10 which is provided with suitable automatic elevating mechanism to maintain the top sheet of the stock pile in the desired position. Suitable sucker tips such as shown, for instance, at 31, and operated by means of mechanism (not shown) actuated by a cam shaft 39, lift the sheets one by one, and deposit them on the tape conveyor 11. Prior to the depositing of the sheet on the tape conveyor, the roller cage 38 is lifted by means of the cam 40 on the cam shaft 39, this cage being again lowered after the sheet is placed below the roller cage. The tape conveyor 11 feeds the sheet under stationary guide bars 41 against disappearance stop fingers 12, which are mounted on a transverse shaft 42. The stop fingers 12 are so located that the sheet S comes to rest against these stop fingers when it is in position above the 25 slideable suction head 13. While the sheet to be printed is in this position superimposed on the suction head 13, and lightly held against the stop fingers 12, the sheet is laterally positioned by means of side guide fingers shown at 43, so as to properly register the sheet with the design mounted on the plate cylinder. Just prior to the completion of the lateral positioning of the sheet, a light suction is applied to the suction head 13 by the conduit 44, which is connected to any convenient source of suction and suction control not shown. This suction is applied to the sheet for the purpose of preventing the lateral overtraveling of the sheet due to the quick engagement of the side guide fingers with the edge of the sheet.

After the sheet has been thus positioned, sufficient suction is applied to the sheet S to firmly hold the sheet in engagement with the head 13 and the disappearing stop fingers 12 are lifted to clear the paper, by suitably timed mechanism, 42a Figures 1 and 5, actuated by the cam shaft 39. The suction head 13 mounted in suitable slideways 45 in the frame of the press, is then caused to move toward the impression cylinder by means of the mechanism 14 which comprises a lever 46 formed with a slot to receive a pin mounted on the suction head, and provided with a roller 47 engaged by a cam 48 which is fixedly mounted on the cam shaft 39.

The suction head feeds the sheet toward the impression cylinder until the leading edge of the sheet contacts the stops 35 on the impression cylinder, whereupon the points of the gripper jaws 30 move downwardly under the control of the gripper actuating mechanism previously described, and seize the sheet between the points of the gripper jaws and the adjacent periphery of the impression cylinder 2. As soon as the gripper jaws engage the gripper edge of the sheet, the suction on the suction head 13 is reduced somewhat in order that the gripper jaws may draw the sheet from the surface of the suction head 13, but the amount of this suction is not reduced sufficiently to permit any dancing, vibration or shifting of the sheet while it is in position on the suction head. After the sheet has been transferred to the grippers on the impression cylinder, the suction is completely released from the suction head and the sheet is carried in engagement with the periphery of the impression cylinder and receives the offset design from the

blanket cylinder. After the transfer of the sheet to the gripper mechanism the suction head is again moved to the sheet receiving position by means of the spring 49, this return being controlled by the contour of the rotating cam 48 as 5 will be understood.

Sheet delivery mechanism

The delivery mechanism, indicated in its entirety at 16 consists of a pair of arms 50 fixed 10 on a shaft 51 pivotally mounted in the press frame 1, and supporting the gripping portion of the delivery mechanism. This shaft is oscillated in timed relation by means of any desired rocking mechanism, not shown, but preferably actuated by a cam shaft 39. Rotatably supported in the lower ends of the arms 50 is a gripper shaft 52 upon which are fixed a plurality of gripper fingers 53. These fingers are adapted to engage a gripper bar 54 secured to the arms 50. A spring 55 is provided which tends to rotate the gripper shaft 52 and the fingers 53 mounted thereon in a counter clockwise direction, as viewed in Figure 4. The gripper fingers 53 are moved to the open position however, when the lever 56, fixed 20 on the shaft 52, strikes against the pin 57 adjustably mounted in the frame 1 of the press as shown in Figure 4. Under the control of a catch, not shown, these gripper fingers remain in the open position as shown in Figure 4, and also in 30 Figure 19, until the gripping face of the finger 53 and the opposed gripping face of the bar 54 straddle the leading edge of the sheet on the rotating impression cylinder. At this instant, the catch is released by suitable mechanism, and 35 the fingers 53 quickly move toward the bar 54 under the influence of the spring 55 thereby firmly gripping the leading edge of the sheet. These fingers maintain this grip upon the sheet until the lever 56 again strikes the adjustable 40 pin 57, at which time the gripping fingers will be moved from the gripping bar and the printed sheet will be deposited upon the delivery pile indicated at 58.

Dampening device

Certain features of the dampening device 17 have been shown and described in complete detail, and claimed in my Patent No. 1,958,593 entitled: Methods of and apparatus for dampening 50 in lithographic presses.

The particularly novel features which form that part of this invention claimed in this application relate to the mounting of this dampening device on the press frame and to the relation 55 of the dampening device to the plate cylinder and other cylinders on the press. Only so much of this dampening device will be described as will be necessary to a full understanding of these features.

Referring particularly to Figures 1, 4, 7, 10 and 11, a boss 60 is provided on the frame member 1b at its upper portion, and mounted in this boss is a hinge pin 61. Pivotaly mounted upon this hinge pin is a hinge bracket 62, the hinge bracket 65 preferably resting on the upper face of the boss 60. The hinge bracket, in turn, is formed with a socket in which a support bar 63 is mounted, this support bar projecting laterally from the hinge bracket 62, and in its normal operative 70 position extending transversely of the press. Likewise extending in a direction transversely of the press is a relatively shorter pin 64 parallel to and spaced from the support bar 63.

Mounted on the support bar 63 is a liquid res- 75

ervoir 65. This reservoir comprises an end frame 66 adjacent the hinge bracket 62 and a second end frame 67 upon the operator's side of the press. These end frames are connected by a troughlike member 68 which is secured to the frames 66 and 67 in a liquid tight manner. Each of the end frames is formed with a socket or recess 69, fitting over the support bar 63, these sockets being provided with a set screw for the purpose of securing the reservoir in fixed relation to the support bar 63, and hence in a fixed relation to the cylinders on the press. The end frame 66 is formed with a rearwardly extending ear 10 which is provided with a hole at its rear end adapted for a sliding fit on the pin 64. In this manner the liquid reservoir 65 is rigidly supported on the bar 63 and is additionally supported against rotation about the bar 63 by means of the engagement of the pin 64 in the ear 10.

20 The reservoir 65 extends across the press for substantially the full width of the plate cylinder 4 and plate 23. Each of the frames 66 and 67 are formed with an upwardly and forwardly projecting ear each formed with an opening to rotatably support a preferably tubular shaft 71 which extends between the end frames 66 and 67, and which is parallel to and located in front of the trough member 68.

25 Mounted on the shaft 71 is a series of siphon capillary wick elements each indicated in its entirety at 72. Each of these wick elements comprises a bracket 73 and capillary liquid absorbing wick elements 76.

30 The bracket 73 is preferably made of metal which will not affect and which will not be affected by the liquid used for dampening. Each of these brackets is formed with a main body portion 77 partly curved concavely downward as shown in Figures 4, 6, and 9, and narrowed or 35 tapered toward its free end terminating at a point 74. Each bracket is likewise formed with a resilient cylindrical portion of a size to engage the outer surface of the tube or shaft 71 with a friction fit, and is so adjusted that the frictional 40 tension of the cylindrical portion on the shaft or tube 71 is not too great to permit the manual rotation of the bracket on the shaft, and so that, at the same time, the bracket will be firmly held on the shaft in any position into which it is moved.

45 For the purpose of manually rotating the brackets 73 on the shaft a finger grip is provided on each bracket.

50 The capillary liquid absorbing wick 76, associated with each bracket, is removably attached to the tapered body portion 77, and is similarly tapered. Another portion of the wick element 76 is freely suspended from the bracket 73 and depends downwardly exteriorly of the trough 68 as is clearly seen in Figures 4, 6, 9, and 12. These 55 depending portions of the wick element 76 are relatively narrow, and are located side by side extending transversely of the press for a distance substantially equal to the width of the plate 23.

55 In order to maintain the liquid in the reservoir at a substantially uniform level a liquid supply chamber 78 is supported on suitable extensions in the end frames 66 and 67. This liquid supply chamber is formed with a discharge spout 79 extending downwardly to the point at which it is desired to maintain the liquid level. Liquid will flow from this spout until the top of the liquid in the reservoir reaches the outlet opening of the discharge spout 79, when no further liquid 70 will flow from the spout until the liquid level 75

again drops below the opening, as will be understood.

5 Mounted for axial and rotatable movement on the support bar 63 are a pair of brackets 80, these brackets being formed with a hub which may be secured in the desired position to the bar 63. These brackets are preferably formed with bearing portions 82 and bearing caps 81.

Slidably mounted in the bearing 82 is a rod 83, Figures 1, 2, 4, 6, 7, 9, 11, 13, and 14. This rod 10 extends across the press for a distance substantially greater than the outside to outside distance of the bearings in the brackets 80. This rod has mounted upon it a pair of forwardly projecting arms 84 spaced apart a distance greater than the 15 width of the plate 23 and upon the forward ends of which are mounted a pair of adjustable blocks 85. These blocks in turn, support a rod 86 which runs across the press and is spaced from and parallel to the rod 83. Supported on the rod 83 and detachably anchored thereto is a distributing member or apron 87 formed of molleton or other relatively soft and flexible liquid absorbent material, which gravitationally rests on the rotating plate 23 mounted on the plate cylinder 4. 25 This apron 87 is formed of a continuous member extending transversely of the press for a distance somewhat greater than the width of the design on the plate 23. Secured to the apron 87 at that edge adjacent the rod 86 is a suspending web of 30 relatively thin and flexible material, this web being suspended from and detachably connected to the rod 86. It will be apparent that the apron 87 gravitationally rides on top of the periphery of the plate cylinder and contacts the cylinder 35 with a pressure that is relatively very light.

The rod 83 is formed at a point intermediate its ends with a downward projection 88, Figures 11 and 13. This projection engages a slot in a lever 89, this lever being pivotally mounted as 40 shown at 90, upon an extension which is integrally formed with or attached to the hinge bracket 62. The lever 89 is provided with a roller 91 mounted at a point intermediate the ends of the lever. This roller is resiliently held in engagement with a face cam 92 by means of a spring 93 as clearly shown in Figure 11. The face cam 61 is rotated by means of a pinion 94 secured to the face of the cam and meshing with a gear 95 rotatably mounted on the plate cylinder shaft 24 50 between the plate cylinder 4 and the frame 1b.

55 As will be evident, the rotation of the face cam 92 will cause the lever 89 to oscillate about its pivot 90 causing the slot at the free end of the lever to move transversely of the press. The engagement of the downward projection 88 of the rod 83 with the slot in the end of the lever 89 will cause the rod 83, arms 84 and rod 86 to move transversely of the press in unison with the lever, this movement will cause the apron 87, mounted 60 on these parts, to reciprocate sidewise across the face of the plate as the plate moves about the axis of the plate cylinder.

65 As previously explained, the shaft or tube 71 upon which the siphon capillary wick elements 72 are mounted, is rotatably mounted in the end frames 66 and 67 of the reservoir 65. A handle 96 is mounted upon one end of the shaft 71, Figures 1, 3, 5, 10, 15, and 16. This handle is provided with a hub 97 which is formed at its under 70 side with a pair of recesses 98 and 99 adapted to engage a pin 100 mounted in the bracket 67. A coil compression spring 101, Figure 10, is interposed between the bracket 66 and a shoulder formed on the shaft 71 as shown in Figure 10, 75

to resiliently force the shaft 71 to the right and cause the recess 98 or 99 to seat upon the pin 100.

In order that the weight of the support bar 63 and the weights of the superimposed apparatus may not be entirely supported on the hinge bracket 62, and in order to properly align the bar 63 and the superimposed dampening apparatus in substantially parallel relation with the plate cylinder, the bar 63 is formed with an extension 63a which is mounted in a seat formed in the frame 1a as shown at 102 Figure 3. In order to maintain the bar 63 in position on the seat 102 I form this support with a shoulder 103 at the one end, and I provide a latch or hook member 104 which extends downwardly past the other face of the bar extension 63a thus preventing unintentional lateral movement of the bar during the operation of the press and insuring the maintenance of the proper alignment of the dampening device with the plate cylinder.

It will now be evident that the entire dampening device including the supply chamber 18, reservoir 65, siphon capillary wick elements 72, apron 87, lever 89, cam 92, pinion 94, and all parts supporting these elements are mounted on the hinge bracket 62 and that this bracket is in turn supported on the boss 60 and pivotally mounted on the vertical hinge pin 61. When the hook 104 is lifted from the position in which it is shown in full lines in Figures 1 and 3, the extension 63a of the support bar 63 is released, and it is possible to move the entire dampening device horizontally about the vertical hinge pin 61, 180 degrees or more from the operating position of the dampening device above the plate cylinder, as is clearly shown in Figure 7 of the drawings.

Operation of the dampening device

The operation of the dampening apparatus is as follows: In the operating position, each wick 76, which has its liquid absorbing end immersed in the liquid in the reservoir 65, will absorb liquid and will draw liquid upwardly by capillary attraction to the highest point of the wick. The liquid will thence be drawn downwardly by a combination of capillary and siphon action through the suspended portion of the molleton wick element 76 until the water reaches the apron 87 to which the water will be transferred by contact and by capillarity. This liquid, delivered by each of the individual wick elements 76 after it reaches the apron 87, is drawn downwardly through the apron to that area of the apron which is in line with the wick and in contact with the plate 23, at which point the liquid is transferred to the moving plate. The conduction of the water thru the apron, from the bottom of the wick 76 to the plate 23 is quite direct and occurs without any appreciable diffusion or lateral spreading.

This transfer of water from the molleton wick element to the apron, and in turn to the plate, serves to keep that area or zone in the plate which moves below the bottom end of the wick element 76, moist, in accordance with the amount of liquid fed by the wick element. If a greater amount of moistening is required by that area or zone of the plate below any wick element 76, the bracket 73 can be rotated in a direction to immerse the absorbing end of the wick more deeply into the liquid. Such an increase in the depth of immersion will produce a greater water transferring capacity of this wick element for the reason that a larger portion of the wick is immersed in the liquid and a greater cross sectional area of the molleton is available on the surface of the

liquid for conducting the liquid upwardly from the surface by capillarity, thus increasing the water conducting function of the wick element. This increased water, is, in turn, transferred to the apron and thence to the surface of the moving plate as described above. If, on the other hand, a lesser amount of moistening is required by that area or zone of the plate below a particular wick element, the bracket 73 of that particular wick element may be rotated to raise 10 the immersed portion of the wick element 76 upwardly so that only a small portion of the wick is immersed in the liquid, and when the cross sectional area of the molleton on the surface of the liquid is smaller it will reduce the flow of 15 liquid in the wick and consequently the amount of liquid delivered to that area of the plate below the discharge end of the raised wick.

It will be understood that all wick elements are usually not immersed to the same extent, as 20 various differences in the moisture requirements of the plate will make it necessary to immerse each wick element to a different extent, as is shown, for instance, in Figure 10. After the desired adjustment of these wick elements has 25 been made to suit the requirements of the plate, no further adjustments or attention of the operator to the dampening of the plate are usually required for any particular plate.

As is well known, it frequently happens that a 30 lithographic press must be stopped for a short period of time either due to a jam caused by the missing of a sheet, or for the purpose of checking of register, inspecting the work, making various adjustments on the press or for 35 other reasons. When the press is stopped, or even when the press is running and no sheets are being fed through the press, it is, of course, desirable to interrupt the feeding of the liquid to the plate in order to avoid the overcharge of 40 the plate with liquid, as will be understood.

This interruption of the feeding of the liquid is particularly desirable when the dampening device is swung from the operative position, shown in Figure 1, to the inoperative position, 45 shown in Figure 7, at which time the absorbing end of the wicks should be removed from the liquid as is clearly shown in Figure 9.

In order to interrupt the flow of liquid in all of the wicks simultaneously the handle 96 50 mounted on the tube 71 is manually turned from the full line position to the broken line position shown in Figure 3. This turning of the shaft 71 causes all of the brackets 73 of the wick elements 72 to raise the immersed portions of the 55 wicks 76 to a point above the liquid as shown in Figures 6 and 9. This lifting of the wick elements above the water does not change the position of any of the wick elements on the tube 71 as these wick elements are frictionally held in 60 position on this tube, as previously explained. When the press is again ready for printing, a simple downward movement of the handle 96 causes the tube 71 to rotate sufficiently to re-immerse the wicks in exactly the same position 65 relative to the surface of the liquid as that which they occupied prior to the interruption of the flow. The engagement of the recess 98 and 99 in the hub 97 of the handle 96 with the pin 100 serves to insure the return of the wick elements 70 to identically the same position each time that the handle is turned downwardly or upwardly. This arrangement makes it possible to adjust the wicks so that each portion of the plate receives exactly the correct amount of moisture, and to 75

interrupt this flow for any period of time, and again initiate this flow without being compelled to individually readjust any of the wick elements.

It will be evident from the construction described, that the area of the apron 87 in contact with the plate 13 may be varied by moving the rods 83 and 86 closer together or farther apart. It will also be apparent that this construction permits the rapid removal of the apron 87, and the substitution of a new or cleaned apron with a minimum of expense or delay. It will also be understood that the apron 87 will immediately be ready for operation upon installation, after it has been moistened by the dampened ends of the wicks 16, without the necessity of making any delicate adjustments.

It will be evident that minor imperfections in the contact of the apron on the plate, or small variations in the liquid conducting capacity of the apron would cause streaks or stripes or variations of moisture coating on the plate. In order to eliminate the possibility of such defects and in order to effect as uniform a distribution of moisture in each zone as possible, I provide automatic mechanism for slightly reciprocating the apron crosswise of the direction of movement of the plate. This mechanism consists, as previously described, of a slidable mounting for the apron supporting rods 83 and 86 and means for reciprocating these rods. The apron will, accordingly, move crosswise of the movement of the plate while maintaining continuous contact with the plate. I prefer to reciprocate the apron relatively slowly and in a manner simulating the speed which might be used by an operator in dampening or cleaning his plate, but with a much shorter sidewise movement so as to prevent the moisture condition of one zone from substantially affecting the moisture condition of the next adjacent zones. I prefer to make at least one or two complete reciprocations during each revolution of the plate cylinder.

In order to prevent any point on the apron from repeatedly travelling over the same point on the plate, I so select the size of the pinion 94 with relation to the size of the gear 95, that the pinion 94 will not make an even number of revolutions for each revolution of the plate.

The lateral reciprocation of the apron 87 does not affect the capacity of the wick elements for transferring liquid to the apron as the lower ends of the wicks 16 shift laterally with the apron and remain in contact with the apron 87 due to the frictional engagement of the wicks with the apron.

This sidewise movement of the apron 87 with relation to the direction of movement of the plate results in a much more effective moistening of the plate than would result from a simple sliding contact.

Drive

The power means for driving this press may be of any desired type, but preferably consists of a belt actuated by a motor, and running over the pulley 9 mounted on the main drive shaft 8. The pulley is mounted on one end of the drive shaft and a hand wheel 105 is mounted on the other or operator's side of this shaft. Intermediate the pulley and hand wheel and between the side frames 1a and 1b are a pair of driving pinions 106 and 107, the pinion 106 serving as the drive for the ink rollers and dampening mechanism and the pinion 107 driving the cyl-

inders and other moving mechanism on this press.

The pinion 106 meshes with the gear 95 Figures 2 and 12. The gear 95, in turn, drives the pinion 94, which rotates the face cam 61 and causes the apron 87 of the dampening device to reciprocate. The gear 95 also meshes with the intermediate pinion 108, which, in turn, drives the gear 109 mounted on the shaft 110, to which the ink roller 6a is also fixed. This gear 109 likewise drives a plurality of ink roller driving gears and idler pinions indicated at 111.

The pinion 107 on the main drive shaft 8, meshes with the gear 112 Figures 8 and 12, which is adjustably fixed to the plate cylinder 4 by means of cap screws passing through slots formed in the gear. This gear 112, in turn, drives the gear 113 which is adjustably fixed to the blanket cylinder. The gear 113, in turn, drives the gear 114 adjustably fixed to the impression cylinder. Gear 114 drives the gear 115 fixed upon and driving the cam shaft 39. This cam shaft as previously pointed out, actuates the suction head, feeder mechanism, tape conveyor and various other mechanisms on the press, not shown.

Summary and advantages

The arrangement of cylinders above described, in which the blanket cylinder is substantially vertically above the impression cylinder and, in which the plate cylinder is located above and laterally of the blanket cylinder, together with the location of the plate inking rollers to the rear of the plate cylinder, makes possible the accessibility of a maximum of the periphery of the plate cylinder, when the dampening device has been shifted to a position remote from the plate cylinder. An inspection of Figures 4 and 7 will disclose the fact that substantially one half of the upper periphery of the plate cylinder 40 will be visible when the dampening device is removed to a position, such for instance, as is shown in Figure 7. It will also be evident that considerably more than one half of the plate will be visible to the operator, and that likewise more than one half of the plate will be easily accessible for the purpose of cleaning or gumming the plate, and making changes or additions in the design of the plate. It will also follow that for inspection or cleaning or gumming of the plate, 50 two half revolutions of the plate cylinder will be sufficient to make the entire plate accessible for these purposes, and it will not be necessary to start and stop the rotation of the plate cylinder, and hence the rotation of the press a 55 large number of times in order that the entire plate might be accessible. It will also be understood that the clamps and screws used for securing the plate on the cylinder are all accessible from one side of the cylinder, and no rotation of the plate cylinder will be required to complete the mounting or adjusting of the plate on the plate cylinder.

Reference to Figure 4 will also disclose the fact that substantially one half of the blanket cylinder is accessible for the purpose of washing the blanket or changing the packing underneath the blanket or making repairs thereon. This proportionately large area of the periphery of the blanket cylinder is accessible even 70 when the dampening device is in place, although the operator might find it more convenient to swing the dampening device away from the plate cylinder while making any substantial changes in the mounting of the blanket on the cylinder. 75

It will also be apparent that the dampening device can very quickly be moved from the operative to the inoperative position and vice versa, and that the flow of water through all of the wicks may be simply interrupted without affecting the relative water conducting capacities of the individual wicks; and it will further be evident that the moisture is applied to the top of the plate cylinder which is the logical place to apply liquid.

It will further be apparent that the dampening device may be moved without any substantially manual effort, and that stop and catch devices are provided for the purpose of properly aligning the dampening device with the plate cylinder, when the dampening device is moved to the operative position.

It will be understood from the description that the automatically reciprocating mechanism is provided for the purpose of reciprocating the apron while it contacts the plate, and that this reciprocating mechanism is adapted to be automatically actuated when the device is in operative position, and that the actuation is automatically discontinued when the dampening device is shifted to any usually inoperative position.

It will also be noted that the periphery of each of the plurality of ink rollers contacting the plate is substantially equal to the length of the design on the plate and that no portion of the periphery of the plate inking rollers contacts the design on the plate more than once during any one impression.

It will further be evident that the gear drive for the cylinders is so arranged that the load on the gear teeth of the gears driving the cylinders will always be on the same side of the teeth. This is effected by driving one of the end gears in the cylinder gear train and causing the gear at the other end of the cylinder gear train to drive the cam shaft which constitutes a rotational resistance which is transmitted through the train of gears on the cylinders and which is greater than any tendency of the cylinder gears to vibrate at a high rate of speed, as a result of any unbalanced condition in the cylinders. This arrangement of gearing thus eliminates the formation of any gear marks due to chattering or backlash of the gears.

50

Modifications

The modification shown in Figure 4a discloses an arrangement of this invention in which certain parts are tilted to utilize the advantages of gravity to a greater extent than is possible with the arrangement shown in Figure 4. Figure 4a shows the parts diagrammatically only, as this modification does not contemplate any essential change in any of the details of the parts of Figure 4. Corresponding parts in these Figures 4 and 4a being indicated by the same reference characters, the structure of Figure 4a will be understood from a brief description.

It will be noted that the essential difference between the arrangement of the parts in Figures 4 and 4a consists of tilting, in a counter clockwise direction, substantially the entire press with the exception of the dampening mechanism and the ink fountain. The sheet feeding mechanism is inclined to a substantially greater degree in Figure 4a, in order to more readily feed sheets to the printing couple, consisting of the impression cylinder 2 and the blanket cylinder 3. It will be noted that the bite of the impression and blanket cylinder is substantially at right angles

to the direction of the sheet being fed to the printing couple, and that, in this modification, the blanket cylinder is located above and to the left with relation to the impression cylinder, and it will also be noted that the plate cylinder 4 is located substantially toward the rear or delivery side of the blanket cylinder; in other words, the plate cylinder is located above the plane of tangency of the impression cylinder and blanket cylinder, and to the rear of the plane passing 10 perpendicularly thru the plane of tangency and including the axis of the impression and blanket cylinders.

The dampening device 17 is maintained in the horizontal position and applies liquid to the uppermost point in the periphery of the blanket cylinder, as in the form of this invention shown in Figure 4. The plate inking rollers 5 contact the periphery of the plate cylinder at a point lower on the periphery of the plate cylinder than in Figure 4, in order that substantially one half of the periphery of the plate cylinder may be accessible for the purpose of inspection, cleaning, etc. The ink distributing rollers 6 and the ink fountain 7 are slightly rearranged to suitably accommodate the shift in the position of the plate inking rollers 5.

The operation of this modification is as follows:

The sheets to be printed are lifted from the stock pile 10 by the sucker tip 37 and deposited upon the member 11 which carries them or permits them to slide downwardly and to the left until the leading edge of the sheet passes over the suction head 13 and engages the disappearing stops 12. In this position the sheet is properly positioned laterally of the press by means of the side guides 43. It should be interpolated that the member 11 need not necessarily be a moving conveyor, as rollers or other equivalent means can be substituted for this conveyor in view of the steeper incline available.

After the sheet has been properly positioned to register with the design on the blanket, the disappearing stops 12 are removed and the suction head 13 is advanced by the mechanism 14, so as to properly feed the sheet to the gripping mechanism on the impression cylinder 2 in the manner hereinbefore explained. The sheet is then printed and fed by the gripping mechanism to the delivery mechanism 16 and deposited upon the delivery pile 58.

This mechanism has certain advantages for the printing of heavy cardboard sheets, tin plates and other materials which are relatively inflexible.

The modification of this invention illustrated in Figures 20 to 23 is applied to a relatively larger plate cylinder than that illustrated in the previously described forms. The arrangement of cylinders and the construction of the liquid supplying device and the moisture applying apron and the means for actuating this apron are substantially the same in this modified form as in the first described form of this invention. The novel features of this modification relate to the additional liquid distributing member and its actuation, together with the mounting of the dampening device. As in the first described form this dampening device is mounted so that it may be shifted to a position remote from the plate cylinder for the purpose of providing access to the plate cylinder at the dampening position, but the details of this mounting constitute a slightly

different embodiment of the principle of this feature of this invention.

This modified form will be briefly described by reference, first, to Figures 20, 21, and 22. The 5 lithographic plate 118 adapted to be coated with ink by the ink rollers 119 is mounted on the plate cylinder indicated at 120. This plate cylinder is located above and rearwardly of the blanket cylinder 121, both cylinders being mounted 10 in suitable bearings in the frame 122, comprising two side frames 122a and 122b.

Pivoted at 123 and 124 are links 125 and 126 respectively. The upper ends of these links pivotally support cross rods 127 and 128. These 15 cross rods support two dampening frames 129a and 129b, one at each side of the press, located above frames 122a and 122b respectively. These frames are held in spaced relation by the rods 127 and 128 and are located in lateral alignment with 20 reference to the press frame 122 and plate cylinder 120 by the links 125 and 126. An additional cross rod 130 extending between the frames and parallel to the cross rods 127 and 128, is supported in the dampening frames.

25 Mounted upon the cross rods 127 and 130 is a reservoir 131 which is generally similar to the reservoirs previously described. The ends of this reservoir are provided with ears 132, these ears being formed with slots adapted to seat upon the rods 127 and 130, and each ear being provided with a set screw for the purpose of fixing the reservoir with relation to said rods. The reservoir contains suitable liquid, and a liquid supply chamber 133 is mounted on the reservoir for 30 the purpose of supplying liquid to the reservoir and maintaining the level of this liquid constant, as previously described.

35 Mounted upon the tube 134 are a plurality of brackets 135 each bracket being independently 40 rotatably adjustable on the tube 134. Each bracket has secured thereto a liquid absorbent wick 136, adapted to absorb liquid from the reservoir and transfer it to the apron 137 contacting the plate 118 and adapted to apply moisture to 45 the plate. This apron is removably secured to the rods 138 and 139 which are reciprocably mounted in the frames 129a and 129b, for movement transversely of the movement of the plate. The apron 137 is anchored to the rod 138 by 50 means of pins or in any other desired manner, and is loosely supported on the rod 139 by means of a suspending web 137a. The clamps 140 made of upper and lower halves, are used to clamp the two rods 138 and 139 together so that these 55 rods will reciprocate in unison.

The rod 137 is formed with a pin 141 on its lower side. This pin is engaged by the slot of a lever 142, the other end of the lever being provided with a roller, and the lever being pivoted 60 intermediate its ends on a pivot 143 supported in the dampening frame 129a. The roller in the lever 142 engages a groove formed in a cam 144, this cam being secured to a gear 145 and both the cam and the gear being rotatably mounted 65 in a hub 146 on the dampening frame 129b. The gear 145 meshes with a gear 147 which is mounted on the plate cylinder, or on the frame of the press.

70 The mechanism so far described, while differing in details, is substantially similar in principle to the device previously described. In this modification, an additional distributing apron is shown at 148. This apron is supported on rods 149 and 150 which are reciprocably mounted in 75 the frames 129a and 129b and are clamped to-

gether for operation in unison by means of clamps 151. The clamps 140 and 151 are provided with vertically projecting pins 152 and 153 respectively. These pins are engaged by slotted ends of a lever 154 pivoted at 155 on the frame 5 129b.

The operation of the elements for feeding the liquid from the reservoir to the apron and from the apron to the plate has already been described. The liquid applying apron 137 is reciprocated by means of the lever 142 actuated by the cam 144 which is, in turn, driven by the gear 145 on the press. This reciprocation of the apron will be parallel to the axis of the cylinder and therefore crosswise or transversely of 10 15 the movement of the plate.

The reciprocation of the distributing apron is effected as follows: The pin 152 oscillates the lever 154 about its pivot 155 which, in turn, causes the rods 149 and 150 to reciprocate, thus 20 reciprocating the apron 148 parallel to and crosswise of the movement of the plate. It will be noted that the direction of movement of the apron 148 is opposed to the direction of movement of the apron 137, and that the apron 148 25 contacts the plate at a point farther advanced with relation to the travel of the cylinder than the point of contact of the apron 137 with the plate. This distributing apron more smoothly equalizes the moisture previously delivered to 30 the plate by the liquid applying apron, and also serves to absorb any excess moisture inadvertently applied to the plate or accidentally accumulated on the plate. It will be understood that the liquid applying apron 137 applies the moisture to 35 the plate subsequent to the printing of an impression upon the blanket and that the moisture is then smoothed by the apron 148, after which the plate is again inked preparatory for the making of the next impression.

40 When it is desired to have access to the plate 118 at the dampening position, for any of the reasons previously indicated, the dampening device, including the reservoir, liquid supply chamber, wicks liquid applying apron, liquid distributing apron, apron reciprocating mechanism and the supports for these elements are shifted from the full line position shown in Figure 20 to the dotted line position shown in the same figure.

45 This dampening device is held in the operative position adjacent to the plate, by means of a latch 157 mounted on the frame and engaging a pin 158 on the link 125.

When the dampening device is removed to the 50 inoperative position shown in broken lines in Figure 20, it may be moved against a stop 159 and a second latch element and pin may be provided for holding the dampening device in the inoperative position if desired.

The dampening device is moved manually and, 55 in order to facilitate the shifting of this device, a spring counter balance is provided consisting of a spring 160 attached to an extension 125a of the link 125 and adjustably anchored to the frame at 162.

60 It will be evident that the mounting described maintains the dampening device in a perfectly level position at all points during the shifting movement, and that the device will maintain its parallel relation with the plate cylinder during 70 its movement.

Figure 23 illustrates another method of securing advantages somewhat similar to those produced by the use of the second distributing apron 75 referred to above. This view shows a roller 161,

covered with molleton or other liquid absorbing material 164. This roller is formed with reduced extensions 165 forming trunnions or pins guided in slots 166 formed in the frame 167. The slots 5 are of sufficient depth to permit the roller 163 to gravitationally ride upon the face of the plate, but will not permit the roller to drop into the gap of the plate cylinder. It will be understood that the liquid supplying apron, liquid feeding 10 device and apron actuating mechanism in Figure 23, are identical with the corresponding device shown in Figures 20, 21, and 22. I have found that this roller very efficiently smooths the moisture and absorbs any surplus or undesired accumulation of moisture on the plate. It will be understood, insofar as the dampening device is concerned, that the present invention relates to the method of mounting of the dampening device on the press and not to the details of the 15 dampening device, and that accordingly, any type of roller or other dampening mechanism, may be used with the herein described mounting without departing from the scope of the appended claims.

25 Many other modifications of this invention and its application will naturally occur to those skilled in this art, and the present disclosures should therefore be considered as typical only, and I desire not to be limited to the exact constructions shown and described.

20 What I claim as my invention is:

1. A mechanism, including a reservoir of liquid, for dampening a plate on a lithographic press, said mechanism being disposed on a support pivotally mounted on the frame of the press, said pivotally mounted support permitting the shifting of the dampening mechanism from cooperative engagement with the plate to a position spaced a substantial distance from the plate, and 30 including means adapted to maintain said reservoir level during said shifting.

2. A plate dampening device for a lithographic press, pivotally supported on the frame of the press, said pivoted dampening device including 45 a reservoir of liquid and means adapted to transfer liquid from said reservoir to said plate, said transfer means including an element adapted to be reciprocated, in combination with mechanism adapted to actuate said reciprocable element.

3. A device for dampening the plate on a lithographic press, said device including a reservoir of liquid and mechanism for feeding liquid from the reservoir to the plate, and being mounted 55 on a hinged support on the frame of the press and movable toward and from the plate, said hinged support being adapted to maintain the reservoir level during its movement.

4. A dampening device for a lithographic press 60 having a plate mounted on a plate cylinder, said dampening device being adapted to supply moisture to substantially the top of the periphery of the plate and being pivotally supported for movement from its moisture supplying position adjacent the top of the plate to a position removed from the plate.

5. A plate dampening mechanism for use in a lithographic press, said mechanism being adapted 70 to be swung about a vertical axis toward and from said plate and being provided with means for holding said mechanism in operative relation with said plate.

6. A mechanism for dampening the plate on a lithographic press, said mechanism being pivoted 75 on a vertical axis on the frame of the press

and adapted to be moved from its dampening position adjacent the plate to a position remote from its dampening position whereby access is provided to the plate at the dampening position.

7. A device positioned on a lithographic press 5 for dampening the plate, including a suspended apron riding on the plate, said device being pivotally mounted on the frame of the press for movement toward and from the dampening position permitting access to the plate at the dampening position.

8. A dampening device positioned to dampen the plate on a lithographic press, said device including an anchored absorbent sheet, means for holding said sheet in dampening engagement 15 with said plate, and individually adjustable elements supplying liquid to said sheet, means adapted to simultaneously interrupt the supplying of liquid by all of said elements without disturbing the relative adjustments of said elements, 20 said device being pivotally mounted for movement toward and from said plate.

9. A dampening device for moistening the plate on a cylinder in a lithographic press, mounted on the frame of the press and positioned adjacent 25 the cylinder and including a suspended absorbent sheet contacting said plate, a reservoir of liquid, and individual elements adapted to transfer liquid from said reservoir to said sheet, said dampening device being so mounted on the frame 30 that it is shiftable from its dampening position a sufficient distance to permit access to the periphery of the cylinder at the dampening position for the purposes set forth.

10. A dampening device for moistening the 35 plate on a rotating cylinder on a lithographic press, mounted adjacent the cylinder and including an absorbent element contacting the plate and adapted to be reciprocated substantially parallel to the axis of the cylinder, mechanism for reciprocating said element, and means for actuating said mechanism, said dampening device being so mounted that it is shiftable toward and from the plate.

11. A dampening device for moistening the plate 45 mounted on the frame of a lithographic press, including an absorbent element contacting the plate and mechanism for reciprocating said element, and means mounted on the frame actuating said mechanism, and a movable support for said 50 dampening device permitting the shifting of the dampening device toward and from the plate, said reciprocating mechanism being automatically disengaged from the actuating means when the dampening device is shifted from the plate. 55

12. A dampening device for moistening the plate in a lithographic press including a reciprocable liquid transferring device, a movable frame for supporting said device in contact with the plate when the movable frame is in one position and 60 for shifting the device to a position spaced from the plate when the movable frame is in another position, means for supplying liquid to the device, and mechanism mounted on the movable frame for reciprocating the device, and means mounted 65 on the stationary frame adapted to actuate the mechanism when the liquid transferring device is in contact with the plate.

13. A dampening mechanism for moistening the plate on a rotating cylinder in a lithographic 70 press, including a reservoir of liquid located adjacent said plate and adapted to apply moisture to the periphery of said plate, said dampening mechanism being supported on a plurality of links on said frame, said links being adapted 75

to shift said dampening mechanism for a substantial distance from the position adjacent to the plate and to main the reservoir level and to maintain the axis of the dampening mechanism substantially parallel with the axis of the plate cylinder during said shifting, whereby the plate becomes accessible at the dampening position for the purposes set forth.

14. A dampening mechanism for moistening a rotating plate in a lithographic press, located adjacent said plate and adapted to apply moisture to the periphery of the plate when the mechanism is in its operative position, a shiftable mounting for said mechanism adapted to shift the mechanism from the operative to an inoperative position, resilient means tending to shift said mechanism into the inoperative position and means for holding the mechanism in the operative position against the tendency of the resilient means.

15. A dampening mechanism, including a reservoir of liquid, for applying moisture to the periphery of the plate on a rotating cylinder in a lithographic press, said dampening mechanism being disposed on a support pivoted on said frame,

said support being adapted for shifting said mechanism from a position adjacent said plate to a position a substantial distance from the plate, and being adapted to maintain the reservoir level and to maintain the axis of the dampening mechanism substantially parallel with the axis of the plate cylinder during said shifting, whereby the plate becomes accessible at the dampening position for the purposes set forth. 5

16. A mechanism for dampening a plate on a lithographic press, said mechanism including a reservoir of liquid and controllable means for transferring liquid by capillarity from said reservoir to said plate, said mechanism being disposed on a support pivotally mounted on the frame 15 of said press, said support permitting the shifting of the dampening mechanism from a position adjacent said plate to a position spaced from and rearwardly above said plate, and being adapted to maintain the axis of the dampening mechanism 20 substantially parallel with the axis of the plate during said shifting, whereby the plate becomes accessible at the dampening position for the purposes set forth.
